UNITED STATES PATENT OFFICE.

EDWARD F. HODGKINS, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ABRADING MACHINE.

Application filed October 15, 1923. Serial No. 668,661.

To all whom it may concern:

Be it known that I, EDWARD F. HODGKINS, a citizen of the United States, residing at Beverly, in the county of Essex and State of Massachusetts, have invented certain Improvements in Abrading Machines, of which the following description, in connection with the accompanying drawings, is a specification, like reference characters on the drawings indicating like parts in the several figures.

This invention relates to abrading machines and is illustrated as embodied in a cylindrical roll especially adapted to be used for buffing or scouring the breasts of Louis heels and also for buffing the scallop which is provided in some heels of this type.

The curvature of the breast of a Louis heel is such that it can be effectively buffed by the use of a cylindrical roll of relatively small diameter, an inch or less, for example. If such a roll is mounted so that one end is free for the presentation of the work, it may also be used for buffing the scallop in the lower end of the breast of the heel. Buffing operations require a softness of touch which makes a pneumatic tool particularly desirable.

Accordingly, an object of the present invention is to devise an improved cylindrical pneumatic buffing tool adapted to be supported on the end of a rotating mandrel.

In the illustrated construction, the tool is so designed that it may conveniently be applied to a "Naumkeag" machine of the type shown in Patent No. 849,838, which was granted April 2, 1907, upon the application of A. W. Rogers.

In the drawings, Fig. 1 is a view in section of one of the heads of such a machine with my improved tool applied thereto;

Fig. 2 is an elevation of the tool with parts of the abrasive covering broken away and showing its application to the scouring of the scallop in the heel;

Fig. 3 is a longitudinal section of the tool;

Fig. 4 is a transverse section showing the application of the tool in scouring the breast of the heel;

Fig. 5 is a perspective view of part of the clamping device for the upper end of the tool; and

Fig. 6 illustrates an auxiliary device for removing readily the clamping device. 55

In machines of the type above mentioned a laterally extending head 10 is provided with bearings 12 and 14 within which is supported for rotation a hollow mandrel 16. Air is supplied to the mandrel through a passage 18, and a pulley 20 is provided intermediate between the bearings to rotate the mandrel. The lower end of the mandrel is threaded externally at 22 at a point removed from the end and internally at 24 near its extreme end. Suitable apertures 26 are provided in the lateral walls, for a purpose to be later explained.

The illustrated buffing tool comprises a hollow cylindrical casing 30, which is closed at its lower end and has molded therein a screw 32 adapted to engage the internal threads 24 to retain the tool upon the mandrel. Owing to the air pressure present, it is necessary to unite the screw with the end of the cylindrical casing with more than ordinary care, and to this end, the head of the screw is provided with transverse openings 34 into which the liquid rubber may flow and with a series of flanges 36 connected by parallel wires 38. When the liquid rubber hardens around this arrangement, the screw is very strongly held in the rubber casing regardless of the pressure of the air tending to push away the tool. 70 75 80

The bore of the casing is substantially the same as the external diameter of the mandrel, and its length is such as to extend substantially to the lower end of the threads 22. In order to retain the casing upon the mandrel and provide an air-tight joint at the upper end, I preferably provide a nut 40, which constitutes an abutment for the upper end of the casing, and a clamping sleeve 42 co-operating with said abutment, said sleeve being split to form fingers 43 and tapered inwardly and weakened at 45, as shown in Fig. 3. Surrounding this tapered sleeve, a clamping cap 44 is provided, which may be screwed down along the mandrel by applying a spanner wrench to the holes 47 and brought into engagement with the outer surfaces of the tapered fingers on the sleeve 42, thereby forcing the cap 44 downwardly to contract the fingers of the sleeve 42 and securely clamp the upper end of the tool to 90 95 100 105

the mandrel. The abutment nut 40 resists any upward expansion of the casing 30 under the compressing action of the sleeve 42 and co-operates with the end surface of the casing to assist in effecting an air-tight joint. Engagement of the inner shoulder of the sleeve 42 with the nut 40 limits the downward movement of the sleeve. A lock nut 46, provided with recesses 48 for engagement by a spanner wrench, is arranged to be brought tightly into engagement with the upper end of the cap thereby locking it in position.

When it is desired to remove the tool from the mandrel, lock nut 46 is first loosened and then the cap 44 is unscrewed and moved upwardly to release the sleeve 42. Sleeve 42 must then be forced upward. In order that this may be done easily and expeditiously, I have provided a special tool 50 which is formed as a cylinder closed at the lower end and provided at the upper end with a rim 52 adapted to engage the lower edge of the cap 44 to lift it out of the way and with a ledge 54 adapted to engage the lower edge of the fingers of the sleeve 42. By this arrangement, the proper sequence of removal is ensured. After the clamping devices have been removed, it is only necessary to unscrew the tool from the mandrel by manual engagement with the lower end.

It will be understood that tool itself is not intended to serve as an abrasive agent, and therefore, for the purpose of buffing or scouring, a covering 60 of abrasive material is applied to the periphery of the tool. Preferably this covering is preformed by overlapping its sides at 62 and securing them together to form a closed cylinder with open ends having an internal diameter slightly larger than the outside diameter of the tool before air pressure has been applied to it. This relation is clearly shown in Fig. 3. Having applied the cover of abrasive material, it only remains to admit air under pressure to the inside of the tool through the lateral openings 26 in an amount sufficient to enlarge the casing 30 frictionally to engage the abrasive covering and to form a cushion of air between the mandrel and the rubber wall of the tool casing 30 as shown in Fig. 4. Having set the machine in motion to rotate the tool, the breast of a heel may be scoured by applying the heel in a horizontal position as shown in Fig. 4 and moving it forward and backward to bring the tool in contact with all parts of the breast of the heel. The curvature of the tool is sufficiently less than that of the breast of the heel to permit access to all parts thereof without danger of creating tool marks. The operator may then tilt the shoe to a vertical position and apply the scallop to the tool in the manner indicated in Fig. 2.

It will be noted that the pneumatic cushion

provided throughout the greater part of the length of the tool does not extend completely to the end of the tool because of the solid rubber portion at the outer end of the elastic cylinder 30. By reason of the fact that the abrasive covering is slightly larger in diameter than the diameter of this solid end, however, a cushion effect will be provided completely to the end of the tool by virtue of the inherent stiffness of the emery cloth, carborundum paper or the like, which may be used for an abrasive covering, and the resulting separation between the solid portion of the elastic cylinder 30 and the abrasive covering when the tool is distended, as shown in Fig. 2.

Having described my invention, what I claim as new and desire to secure by Letters Patent of the United States is:

1. A pneumatic buffing and scouring tool comprising a hollow mandrel provided with an air outlet opening near the tool receiving end, an elastic casing for said mandrel formed as an elongated cylinder closed at one end and provided with means for attaching the same to the mandrel at the closed end of the cylinder, and means for clamping the open end of the cylinder to the mandrel at a point beyond the outlet opening.

2. A buffing tool comprising an elongated cylinder of elastic material closed at one end and open at the other, and means for attaching said cylinder to a mandrel, said attaching means being positioned inside the cylinder at the closed end thereof.

3. In a pneumatic buffing tool adapted to be mounted upon a rotating, hollow mandrel, means to secure an elastic casing on said mandrel comprising a clamping mechanism having a split sleeve, a clamping ring surrounding said sleeve adapted to contract the same, one of said members being provided with a tapered surface, and means for bringing said clamping ring forcibly into engagement with the split sleeve.

4. A pneumatic buffing tool comprising a hollow cylinder of elastic material closed at one end and open at the other, and means for securing said cylinder to a rotating mandrel comprising a screw projecting upwardly within the closed end of the cylinder, said screw having a plurality of flanges adapted to be molded into the material of the closed end of the cylinder whereby it is rigidly held in position and the screw may be rotated by engaging the cylinder.

5. In a machine of the class described, a hollow mandrel having an air outlet opening and mounted for rotation in the head of the machine, means for supplying air to the interior of said mandrel, a closure for the end of the mandrel comprising an elastic elongated cylinder provided with a closed end, means for securing the closed end of the cylinder to the mandrel, means for clamp-

- ing the open end of the cylinder to the mandrel, and an abrasive sleeve constructed and arranged to be slipped over the elastic cylinder before the same is inflated and held 5 in position solely by reason of its engagement with the distended walls of the cylinder after the same has been inflated.
6. In a machine of the class described, a buffing tool for the breast and scallop of a 10 Louis heel comprising an air-retaining elongated cylindrical casing whose radius of curvature is substantially the same as that of the scallop of the heel and considerably less than that of the breast of the heel, said 15 tool being supported only at one end, a cylindrical abrasive covering for said tool having an internal diameter greater than the diameter of said casing when uninflated, and means for supplying air under pressure 20 to the interior of the tool to provide a cushion for the abrasive covering and to expand the casing to bring it against the abrasive covering so as to maintain it in position on the tool.
- 25 7. In a machine of the class described, a rotatably supported hollow mandrel, means for supplying compressed air to said mandrel, said mandrel having a projecting unsupported end provided with an air outlet 30 opening, a cylindrical elastic casing having a closed end arranged to be positioned upon the unsupported end of the hollow mandrel, and means for clamping the upper end of said elastic casing to the mandrel above the 35 air outlet opening so as to form an air-tight joint with the mandrel to allow the expansion of the casing under the pressure of the air.
- 40 8. A pneumatic buffing tool comprising a hollow mandrel, an elastic casing covering part of said mandrel, and means for clamping one end of said elastic casing to the mandrel comprising a sleeve whose end is split to provide a plurality of pointed fingers each 45 of which is tapered from its outer end toward the point of its connection with the solid end of the sleeve to render the fingers more flexible.
9. A buffing tool comprising a hollow
- mandrel, an elastic casing surrounding said 50 mandrel, an abutment on the mandrel adapted to engage the end of the elastic casing, a clamping sleeve provided with a plurality of spring fingers, and means for bringing said fingers forcibly into engagement with the outer surface of the elastic casing at a point adjacent to said abutment. 55
10. A pneumatic buffing tool comprising a supporting mandrel, an elastic casing on said mandrel provided with a closed and 60 solid outer end, a cylindrical abrasive covering for the periphery of said tool slightly larger in internal diameter than the diameter of the closed end of the elastic casing and adapted to be held in position by 65 expansion of the elastic casing above its closed end whereby said abrasive covering will be supported by a cushion of air pressing part of the casing against the covering above the solid end of the elastic casing and 70 will be slightly separated from the closed end of the tool surrounding the solid portion thereof, thereby leaving the outer end of said covering unsupported to furnish a flexible abrading portion overlying the solid 75 end of the casing by virtue of the inherent stiffness of the covering.
11. In a machine of the class described, a pneumatic buffing tool comprising a hollow mandrel rotatably supported at one end, 80 said mandrel having an air outlet opening adjacent to its unsupported end and an abutment above the air outlet opening, a cylindrical elastic casing having a closed end adapted to be positioned over the unsupported end of said hollow mandrel, a cylindrical abrasive covering surrounding said 85 casing, and means cooperating with said abutment to clamp the casing to the mandrel so as to form an air-tight joint and permit the expansion of the casing by air under pressure supplied through the mandrel thereby to press the casing against the cylindrical abrasive covering surrounding the casing to retain said covering upon the tool. 90
- 95 In testimony whereof I have signed my name to this specification,

EDWARD F. HODGKINS.
